DRILL GRINDER

Elizabeth E. Haynes, Brighton, Mass.

Application July 11, 1947, Serial No. 760,257

4 Claims. (Cl. 51—56)

1

This invention relates to grinding machines, and more particularly to a machine for grinding masonry drills.

It is a principal object of the invention to provide a hydraulically operated device for grinding both front angles of a masonry drill. In a preferred embodiment of the invention, two tables are arranged to move intermittently along converging paths, and each table carries a cup wheel that is adapted to grind the tip of a masonry drill.

The invention is illustrated in the accompanying drawings, but it is understood that modifications may be made therein without departing from the spirit of the invention as hereinafter claimed.

Figure 1 represents a plan view of the new and improved grinder.

Figure 2 is an enlarged fragmentary vertical section of the grinder, taken along the line 2—2 of Figure 1.

Figure 3 is an enlarged fragmentary vertical section through the grinder, taken along the line 3—3 of Figure 1.

Figure 4 is a horizontal section, taken through the line 4—4 of Figure 2.

Figure 5 is a side elevation of the chuck for holding the drill.

Figure 6 is a rear elevation of the structure shown in Figure 5.

Figure 7 is a front elevation of the structure shown in Figure 5.

Figure 8 is a plan view of the structure shown in Figure 5.

As shown in the drawings, the invention is shown applied to a horizontal bed plate 100. Two tables 101 and 102 are movable horizontally on the bed plate 100, and for this purpose the bed plate 100 may be provided with two pairs of tracks 103 and 104 for the table 101, and tracks 105 and 106 for the table 102. As illustrated, these pairs of tracks converge toward each other, so that the tables 101 and 102 may approach the angle intermittently.

Hydraulic means is provided for actuating the tables 101 and 102. This means comprises a cylinder 1, a piston 2 operable in the cylinder 1, and a piston rod 3. Each of the tables 101 and 102 is provided with such a hydraulic system.

Each cylinder 1 is bolted to the bed plate 100 by means of one or more brackets 4. Each cylinder is coupled by a pair of couplings 5 to two conduits 6, which will be described more particularly hereinafter. Each piston rod 3 is fastened to its table 101 or 102 by suitable fastening means 8.

2

Consequently, as the piston 2 is actuated in the cylinder 1, the cylinder 1 will remain stationary with the bed plate 100, and the piston rod 3 will move the table 101 or 102.

5 The tables 101 and 102 are movable with respect to a drill held by means to be described more particularly hereinafter, and mounted on each of the tables 101 and 102 is a cup wheel 9 designed to grind the drill. Each cup wheel 9 is mounted on a metal mounting plate 10 secured to a horizontal shaft 11. The shaft 11 is journaled in a housing 12 that may be provided with ball bearings 14. The housing 12 is carried in an upright extension of the table 101 or 102. The cup wheel 9 is provided with a centering shaft 15 to properly align the cup wheel 9 with the shaft 11. The cup wheel 9 is fastened to the mounting plate 10 by means of one or more screws 16. A pulley 17 is fixed at one end of the shaft 11, and a belt 18 transmits power thereto from a motor 19 supported on the horizontal face of the table 101 or 102. The bed plate 100 is provided with a horizontal opening 26 to permit connection of the conduits 6 to the cylinders 1.

10 A chuck 27 is designed to hold the work to be ground. The chuck 27 is provided with a collet 28, which has a series of slots 29 to facilitate insertion and removal of a tool 30, in this instance a masonry drill. The face of the chuck 27 contains an arcuate channel 31 which is marked with graduations 32. A set screw 33 holds an indicator 34 in any desired position in the channel 31. The indicator 34 will thereby indicate any desired clearance angle to be applied to the drill 30. The chuck 27 rests on a base plate 35, and the bottom plate 36 of the chuck is dovetailed to slide in the base plate 35. The bottom plate 36 is provided with a longitudinal hole 37 to accommodate a feed 15 screw, as will be described more particularly hereinafter.

15 The small end of the collet 28 is provided with threads 39 to engage similar threads of a base 40 at the rear of the chuck 27. This base 40 is provided with a reduced portion 41. The rear portion of the base 40 contains a series of holes 42 adapted to receive a sharp pointed instrument whenever the collet 28 is screwed into the chuck 27 or removed therefrom. A lever 43 is pivoted on a pivot pin 44 for the purpose of opening and closing the collet 28. When the collet 28 is screwed into the base 40 the proper amount, and the lever 43 is pushed down, the slots 29 in the collet 28 will be closed and the collet 28 will be locked. When the lever 43 is moved up, the slots

29 will be opened, and the drill 30 can then be withdrawn. The lever 43 is bifurcated, and the furcations are provided with a pair of inwardly projecting pins 45 which are accommodated in the reduced portion 41 of the collet base 40, to permit the collet 28 to be drawn into the chuck 27 and to be propelled therefrom.

The chuck 27 and its associated members are pivoted on two horizontal pivot pins 47 so that the chuck may be positioned horizontally or vertically for easy loading and unloading.

A feed wheel 48 is mounted at one end of a feed screw 49 that screws into the bottom plate 36 through the threaded hole 37. Obviously, as the wheel 48 is rotated in one direction or the other, the bottom plate 36 and the chuck 27 mounted thereon will be fed toward the grinding wheel 9 or away therefrom. The feed screw 49 itself has no axial movement, being prevented from such movement by a collar 50.

The hydraulic system for each of the tables 101 and 102 is similar.

The conduits 6 lead to a hydraulic cylinder 52, in which a piston 53 is horizontally reciprocable. This cylinder 52, as hereinbefore indicated, is below the surface of the bed plate 100. A pump 54, operable by a motor shaft 55, is designed to pump oil or similar fluids into the cylinder 52. The motor shaft 55 rotates a drive wheel 56, positioned in a housing 57, to pump the oil through the hydraulic systems. The cylinder 52 is provided with a pair of relief tubes 58, and the piston shaft attached to the piston 53 has a reduced portion 59 to permit the oil to go from one side of the cylinder 52 to the other. The end of this piston shaft is provided with a pivot 60, for a purpose to be described hereinafter, and an oil tank 61 provides a reservoir of oil for the pump 54.

One of the tables 101 and 102 is provided with a pair of dogs 71 and 72, that are adjustable to any desired feed. That is, the dogs 71 and 72 may be moved toward each other or away from each other to shorten or lengthen the movement of both the tables 101 and 102. A reverse lever 73 operates a shaft 74 that is connected to the connecting rod of the hydraulic cylinder 52. The reverse lever 73 is mounted on a base 75 formed on the bed plate 100.

In the operation of the device, the tables 101 and 102 are simultaneously operated to bring their grinding wheels 9 intermittently against the tip of the drill 36, which has already been adjusted in the chuck 27. When the valves 81 and 82 in the cylinder 52 are open, the fluid passing through the open valve 81 will exert pressure through the conduits 6 to drive the pistons 2 in the cylinder 1 to the right, carrying the tables 101 and 102 to the right. At the same time, the oil will be forced out of the other end of the cylinder 1 and through the open release valve 82. After the tables 101 and 102 have moved to the limit of their travel to the right, the dog 71 will push the lever 73 to the right, actuating the shaft 74 about the pivot 60 to move the connecting rod of the cylinder 52 to the left. This will close the valves 81 and 82, and open the valves 83 and 84 in the cylinder 52. The hydraulic pressure will now be exerted to move the tables 101 and 102 to the left, and this motion of both tables will be repeated intermittently until the desired grinding has been effected.

I claim:

1. A machine for grinding two different faces of a tool lying in intersecting planes, said machine comprising a relatively stationary bed, a

pair of tables mounted on said bed for movement toward and away from the intersection of said planes, means for positioning the tool to be ground, powered grinding wheels mounted on said tables for engaging the related faces of the tool, and operating means for alternately moving said tables toward and away from the intersection of said planes whereby one of said grinding wheels moves toward the intersection and across the related face of the tool while the other grinding wheel moves away from the intersection and across the face of the tool related thereto.

2. A machine for grinding two different faces of a tool lying in intersecting planes, said machine comprising a relatively stationary bed, a pair of tables mounted on said bed for movement toward and away from the intersection of said planes, means for positioning the tool to be ground, powered grinding wheels mounted on said tables for engaging the related faces of the tool, and operating means for alternately moving said tables toward and away from the intersection of said planes whereby one of said grinding wheels moves toward the intersection and across the related face of the tool while the other grinding wheel moves away from the intersection and across the face of the tool related thereto, said operating means comprising separate operating components operatively connected between each of said tables and said bed, continuously operable drive means effectively connected directly to both of said operating components for operating the same in either direction, and control means operating between each table and said base plate and effectively connected to said continuously operable drive means whereby the amplitude of movement and the direction of movement of said tables are determined by the arrival of said tables into positions corresponding to terminals of the predetermined amplitudes of their movements relative to said bed.

3. A machine for grinding two different faces of a tool lying in intersecting planes, said machine comprising a relatively stationary bed, a pair of tables mounted on said bed for movement toward and away from the intersection of said planes, means for positioning the tool to be ground, powered grinding wheels mounted on said tables for engaging the related faces of the tool, and operating means for alternately moving said tables toward and away from the intersection of said planes whereby one of said grinding wheels moves toward the intersection and across the related face of the tool while the other grinding wheel moves away from the intersection and across the face of the tool related thereto, said operating means comprising separate operating components operatively connected between each of said tables and said bed, continuously operable drive means effectively connected directly to both of said operating components for operating the same in either direction, and control means operating between each table and said base plate and effectively connected to said continuously operable drive means whereby the amplitude of movement and the direction of movement of said tables are determined by the arrival of said tables into positions corresponding to terminals of the predetermined amplitudes of their movements relative to said bed, said separate operating components comprising hydraulic jacks comprising cylinders secured to said tables and pistons secured to said bed, said continuously operable driving means comprising a hydraulic cylinder, a valving piston therein, and

conduits leading from hydraulic cylinder to said hydraulic jacks whereby said jack pistons are moved in one set of directions in one position of said valving piston and in another set of directions in another position of said valving piston, and powered hydraulic fluid supply means for said hydraulic cylinder.

4. A machine for grinding two different faces of a tool lying in intersecting planes, said machine comprising a relatively stationary bed, a pair of tables mounted on said bed for movement toward and away from the intersection of said planes, means for positioning the tool to be ground, powered grinding wheels mounted on said tables for engaging the related faces of the tool, and operating means for alternately moving said tables toward and away from the intersection of said planes whereby one of said grinding wheels moves toward the intersection and across the related face of the tool while the other grinding wheel moves away from the intersection and across the face of the tool related thereto, said operating means comprising separate operating components operatively connected between each of said tables and said bed, continuously operable drive means effectively connected directly to both of said operating components for operating the same in either direction, and control means operating between each table and said base plate and effectively connected to said continuously operable drive means whereby the amplitude of movement and the direction of movement of said tables are determined by the arrival of said tables into positions corresponding to terminals of the predetermined

amplitudes of their movements relative to said bed, said separate operating components comprising hydraulic jacks comprising cylinders secured to said tables and pistons secured to said bed, said continuously operable driving means comprising a hydraulic cylinder, powered hydraulic fluid supply means for said hydraulic cylinder, conduits leading from said hydraulic cylinder to said jack cylinders whereby said jack piston of each jack can be moved in opposite directions, valving piston in said hydraulic cylinder arranged to be moved to positions in said hydraulic cylinder to occlude some of said conduits while opening others of said conduits whereby to determine the amplitude and direction of movement of said jack pistons and the tables associated therewith, and means effectively connecting said valving piston with said control means.
